UNITED STATES PATENT OFFICE.

ALEXANDER MORRIS AND VICTORIA L. MORRIS, OF SAN FRANCISCO, CALIFORNIA.

SET-SHIFT PARALLEL RULER.

Application filed February 12, 1926. Serial No. 87,887.

This invention relates to improvements in drawing instruments and has particular reference to a device for holding drawing instruments such as triangles, irregular curves 5 or such other instruments as may be designed to assist in forming a line.

Another object of this invention is to produce a device of this character which is easy to manipulate, convenient in arrangement and accurate in repeating lines which 10 have been established.

An additional object of this invention is to produce a device wherein the section lines may be uniformly constructed having 15 intervals of a definite measurement, thus avoiding the tedious loss of time usually experienced in section line work.

Another object is to provide means whereby the drawing tools may be nested in the 20 device so as to facilitate the transportation of the same.

A still further object of this invention is to produce a device of the character described which is simple in construction, economical to manufacture, compact in the arrangement of its parts and highly efficient 25 in operation.

Other objects and advantages will be apparent during the course of the following 30 description.

In the accompanying drawings forming a part of this specification, and in which like numerals are employed to designate like like parts throughout the same,

35 Figure 1 is a top plan view of our device showing the same in actual use and partly broken away,

Figure 2 is a rear view of the box-like structure,

40 Figure 3 is a front elevation of Figure 1,

Figure 4 is an enlarged detail cross section taken on the line 4—4 of Figure 5, showing the handle 36 in cross section,

45 Figure 5 is an enlarged detail cross section taken on the line 5—5 of Figure 4, and showing the operating mechanism,

Figure 6 is a cross section taken on the line 6—6 of Figure 5,

50 Figure 7 is a bottom plan view of the actuating wheel, and

Figure 8 is a fragmentary detail view showing the ratchet mechanism.

55 In the accompanying drawing wherein for the purpose of illustration is shown a preferred embodiment of our invention, the

numeral 5 designates a box-like structure having a hinged lid 6. Within this box-like structure, pencils 7 may be placed or other drawing instruments, as the case may be.

At 8, we have shown a partition extending the length of the box-like structure so as to form a compartment 9 in which the rack 11 is adapted to operate. This rack is secured to a substantially V shaped plate 12, which plate is, in turn, secured to a filler 13 adapted to be slidably held in a slot 14 formed longitudinally along the rear face of the box-like structure.

A plate 16 is, in turn, secured to the 70 filler 13 and has a base portion 17 formed at right angles thereto.

Referring now to Figures 1 and 3, it will be noted that the plate 16 has extending outwardly therefrom, triangular shaped lugs 75 18 and 19, through which slidably supported bolts 21 pass. These bolts have coiled thereon springs 22 and have their lower extremity secured to a bar 23, which is U-shaped as best noted in Figure 5. The purpose of forming this bar 23 in a U-formation is to retain a rubber gripper 24 therein.

This rubber gripper is adapted to contact a rubber sheet 26 which is held to the plate 16 by a plate 27. This plate 27 is so formed 85 as to have thereon a series of retaining slides 28. These retaining slides extend over and engage the bar 23.

At 29 we have shown a handle which is attached to the bar 23 in such a manner that 90 when the handle 29 is lifted upwardly the bar 23 will be raised against the action of the springs 22.

Again referring to Figure 5, it will be noted that the gear 31 meshes with the rack 95 11, which gear is secured to a shaft 32 extending upwardly through the box-like structure and rotatably held in a bearing 33. The upper end of this shaft is squared as at 34 so as to retain thereon a knurled actuating wheel 36. This actuating wheel is provided with a plurality of notches 37, upon one side thereof and a plurality of notches 38 on the opposite side thereof. The V-shaped plate 12 before referred to serves 100 to take up lost motion of the rack 11 against the gear 31.

By viewing Figure 3, it will be noted that the notches 38 are spaced a considerable distance apart, while the notches 37 are in 110

close proximity to each other. This actuating wheel is retained upon the shaft 32 by a retaining nut 39.

At 41 we have shown a ratchet tooth 5 mounted upon a spring 42 which is secured to the top of the box-like structure, as at 43. The numeral 45 indicates buffers provided on the bottom of the box which serve to prevent a marring of the work upon 10 which the box may rest.

The result of this construction is that when in use this device as a whole is placed upon the drawing-board, a drawing instrument such as an angle or French curve is 15 inserted in the device by lifting upon the handle 29, thereby drawing the member 24 away from the rubber sheet 26, which will permit the instrument, as for instance, the angle "A" of Figure 1 to be inserted as 20 shown in dotted lines at "B" in Figure 5.

By now manipulating the actuating wheel 36, the angle may be moved along the device, with the result that a series of parallel lines may be drawn as shown at "C" in Figure 1, 25 or at "D" as the case may be, it being assumed that the angle has been turned to a different position previous to the drawing of the lines "D".

Of course, it is possible to employ two angles in the device at the same time. When 30 it is desired to vary the spaces between the lines being drawn, the operator may turn the operating wheel so that two clicks of the ratchet are heard instead of one, or by 35 removing the operating wheel and turning the same over, a different spacing may be accomplished.

It will thus be seen that we have constructed a device which will accomplish all 40 of the objects above set forth.

It is to be understood that the form of our invention herewith shown and described is 45 to be taken as a preferred example of the same, and that various changes in the shape, size and arrangement of parts may be resorted to without departing from the spirit of the invention or the scope of the subjoined claims.

Having thus described our invention, we 50 claim:

1. A device of the character described comprising means forming a supporting surface, a rack bar slidably mounted on said surface, means supporting said bar comprising 55 an elongated member angular in cross-section secured to and movable therewith, means mounted on said first-named means for moving said rack bar in successive steps,

a plate on said second-named means and adapted to be moved by the actuation of said 60 rack bar, and means for frictionally securing a drawing instrument to said plate.

2. A drawing instrument comprising a box-like structure, a gripping means for a line defining element slidably mounted at 65 one side of said structure, a rack bar connected to said gripping means, and means for successively moving said rack bar comprising a shaft pivotally mounted in said 70 structure, a gear fixed to said shaft and adapted to mesh with said rack bar, and a rotatable member for actuating said shaft.

3. A device of the character described, a box-like structure having a slot formed in one side thereof, a filler slideable in said slot, 75 a substantially V-shaped plate secured to said filler inside said structure, a rack bar secured to said V-shaped plate, an angular plate secured to said filler exteriorly of said structure, a gear mounted in the box adapted 80 to mesh with said rack bar, manually actuatable means for rotating said gear in successive steps so as to move said rack bar longitudinally, a U-shaped bar secured to said angular plate, a resilient gripping member secured to said bar, and a handle for moving said gripper into and out of contact with 85 said angular plate.

4. A device of the character described, a box-like structure having a slot formed in 90 one side thereof, a filler slideable in said slot, a substantially V-shaped plate secured to said filler inside said structure, a rack bar secured to said V-shaped plate, an angular plate secured to said filler exteriorly of said 95 structure, a gear mounted in the box and adapted to mesh with said rack bar, manually actuatable means carried by said structure for rotating said gear in successive 100 steps so as to move said rack bar longitudinally, a U-shaped bar secured to said angular plate, a resilient gripping member secured to said bar, a handle for moving said gripper into and out of contact with 105 said angular plate, said manually operating means including a detachable actuating wheel equipped with notches on its upper and lower surfaces, and means positioned on 110 said box-like structure and co-operating with the notches on one side of the actuating wheel for audibly indicating the degree of movement of said actuating wheel.

In testimony whereof we affix our signatures.

ALEXANDER MORRIS.
VICTORIA L. MORRIS.
